FOLLOWER FOR FILE DRAWER

William A. Dunlap, Corry, Pa., assignor to Corry-Jamestown Manufacturing Corporation, Corry, Pa., a corporation of New York

Application February 7, 1945, Serial No. 576,642

4 Claims. (Cl. 129—30)

1

This invention relates to an improvement in a filing cabinet drawer, and more particularly to a follower therefor adapted to hold cards, files of papers, etc., in a substantially upright position.

It has been the practice in structures of this kind to provide a follower that was either supported by the drawer through the use of rearwardly or forwardly extending support or guide members. The followers having rearwardly extending support or guide members have not been considered suitable, since these members prevented movement of the follower to the rear of the drawer. Thus, a certain amount of space was unavailable for files and, when this space is multiplied by four drawers in a cabinet and several cabinets, it becomes of considerable importance. Followers having support or guide members extending forwardly thereof have been provided with one of two types of locking or securing structures by which to prevent undesirable rearward movement of the follower when in place to hold papers or other file material. In some instances, the channels, formed in the drawer sides for the purpose of receiving the follower support or guide members, have included, in one or more flanges thereof, a series of apertures or ridges. An operable element, having one or more teeth projectible into the apertures, or a surface complementary to the ridges, was provided and made operable through a release lever conveniently located on the follower. A further structure of this nature is the L. A. Vanderhoof Patent No. 2,081,470, wherein the channel of the drawer was smooth but the channel engaging member of the follower was formed with teeth adapted to engage one of the channel flanges to prevent inadvertent movement of the follower. In those structures having apertures or ridges in the drawer channel, it is found that the follower cannot always be adjusted to render exactly the desired compactness of the drawer contents and, further, that movement of the follower from one position to another, caused considerable noise and, in time, wear of these surfaces prevented their proper functioning to hold the follower against pressure of the drawer contents. In the structure disclosed in the above mentioned patent, the teeth of the movable member, carried by the follower, in time produced uneven or rough surfaces on a flange of the drawer channel, and the follower not only made undesirable noise when adjusted, but would not function to secure the drawer contents in any and all desired compressed conditions.

It is the purpose and principal object of the present invention to provide a drawer follower

2

with means for securing it in any position of adjustment throughout the length of the drawer. It is also an object of the invention to provide securing means for a drawer follower that will function to hold the drawer contents in any desired state of compactness; that is, from an extremely loose to an extremely compact condition. It is another object of the invention to provide means for securing a drawer follower that is entirely silent in operation and that, by reason of its structure, does not, throughout use, cause such wear to take place as would detract from its operation, or render it objectionable due to noisy operation. It is also a very important object of the invention to provide securing means for a drawer follower that is of the nature of an anti-friction clamp and which, in operation, relies solely on the pressure of two elements upon opposite surfaces of another element for its action.

10 Other objects and advantages of the invention will be more fully understood and appreciated from a consideration of the following specification, taken in conjunction with the accompanying drawing; and in which

20 Fig. 1 is a perspective view of a file drawer with a follower and securing means therefor, embodying one form of the invention, parts of the drawer being broken away to more fully disclose certain of the follower's structural details.

25 Fig. 2 is a fragmentary perspective view of the follower showing the mounting and securing mechanism therefor and the manner in which it is mounted in the drawer;

30 Fig. 3 is an enlarged fragmentary vertical transverse sectional view of the drawer channel with the follower parts mounted therein;

35 Fig. 4 is a fragmentary edge view of the follower showing the support and securing means in position to lock or secure the follower against movement with respect to the drawer;

40 Fig. 5 is a view similar to Fig. 4 showing the securing mechanism in released position, preparatory to movement of the follower along the drawer; and

45 Fig. 6 is an enlarged fragmentary vertical sectional view showing the lever by which the follower securing means may be actuated from the position shown in Fig. 4 to that of Fig. 5.

50 Referring to the drawing, the invention is shown mounted in a drawer, generally indicated by the reference numeral 10. The drawer includes the usual front 11, rear 12, and side walls 13. The side walls 13 are formed with longitudinally extending channels 14 which serve the dual purpose of providing space in which to mount a

follower support and guide, as well as rigidify the side walls. In the present adaptation of the invention, the drawer channels 14 are each formed with a base wall 16, vertical wall 17 and top wall 18 that corresponds to the base wall. The top wall may terminate in a depending flange 19 which serves to restrict, to some extent, the opening 21 of the channel.

A follower 22 consists of an upright plate that may terminate at its upper end in a rearwardly rolled portion 23. The front surface of the plate is unbroken and smooth for contact with the file contents of the drawer. Somewhat above the horizontal center and adjacent its vertical edges, the follower is provided with permanently attached supports or guide shoes, generally indicated by the numeral 24. These supports each include an arm 26, applied to the rear face of the follower in substantially the position shown in the drawing, being secured thereto in any suitable manner, as by welding. One end of this arm terminates in an angularly disposed flange 27, having a generally triangular opening 28 therein. The support 24 includes an arm 29 that extends at right angles to arm 26 and forwardly of the follower 22.

Each arm 29 is of channel form, having upper and lower flanges 31 connected by a vertical wall 32. The arm 29, towards its outer end, is so formed that the flanges 31 converge slightly as indicated at 33, and then diverge to form short flanges 34 having the original spacing of the flanges 31. As may be seen in Fig. 3 of the drawing, the channel shaped arm 29 is adapted to be received in the space 21 of the drawer channel 14 in such a manner that it cooperates with said channel to form an enclosure.

Mounted in the space within each arm channel 29 is an adjustable plate 36. At one end this plate terminates in a laterally offset portion 37 having a downwardly opening recess or slot 38 therein. The other end of each plate is tapered, substantially in conformity with the converging flanges 33 of the arm 29. Mounted at this end of the plate are a pair of rollers 39, or their equivalent. As shown in the drawing, the rollers are of the floating type, being held in place by pairs of lugs 41 which may be attached to, or formed from, the plate 36. These lugs confine the rollers only against movement lengthwise of the plate, the plate proper and the wall 17 of the drawer channel 14 serving to prevent lateral displacement of said rollers. Forming a part of, or secured to, the inner face of the wall 17 of drawer channel 14 is a rail 42 which, in the present disclosure, is substantially midway between the top and bottom channel flanges 16 and 18. As will be noted, two rollers 39 are carried by each of the plates 36. One of these rollers, when the structure is assembled, is located above the rail 42 and the other therebelow.

At the rear of the follower, a rocker bar 43 is located, the ends thereof projecting through the triangular openings 28 of flanges 27. At its extreme ends, the bar 43 is formed with lugs 44 that project into the slots 38 of plate flanges 31. Centrally, the bar 43 is fitted with a release lever 46 that includes an upper finger portion 47, channel 48 in which to receive the bar, and lower portion 49. The upper and lower portions 47 and 49 are so relatively disposed that the entire lever may be rocked, the bar 43 serving as an axis for such movement. Since it is desirable to yieldingly retain the lever in a position such that the follower will be locked or secured against movement with 75

respect to the drawer, spring means is provided. This means may take the form of a looped, U-shaped spring 51, the closed end 52 being engaged with the portion 48 and the open ends 53 anchored to the follower in any suitable manner, as by engagement with struck-out portions 54. For convenience of assembly, the bar 43 may be formed in two parts, one part being permanently attached to the lever 46 and the other part joined thereto in any suitable manner, as by one or more screws 56.

The structure of the invention having been described, the general assembly and operation thereof is set out as follows:

Following permanently securing the supports or guide shoes 24 to the follower, the rocker bar 43 and lever 46 are assembled. Plates 36, with their rollers 39 in place, may then be mounted in the shoes, the slotted ends of the plates receiving the ends of the bar 43. Although not heretofore mentioned, it is common in drawers of the type disclosed, to cut away, for a short distance, corresponding portions of the top and depending flanges 18 and 19 adjacent the front 11 of the drawer. The purpose of this, obviously, is to facilitate inserting the follower in its entirety into the drawer, the shoes 29 dropping into place in the channels 14. The rails 42 also terminate somewhat short of the front 11. This structure in no wise affects the usefulness of the follower, since it seldom, if ever, occurs that the drawer contains so little file matter that the follower is required to be in its forwardmost position in the drawer.

After installing the follower, the lever 46 is tilted against tension of the spring 51 from the position of Fig. 4 to that of Fig. 5. This movement rocks bar 43, causing rearward movement of plates 36 with respect to arms 29 of the guide shoes 24. Rearward movement of the entire follower causes rollers 39 to be positioned above and below rail 42 and it will be noted, in this position of the parts, that the rollers are loose with respect to the adjacent faces of the rail 42 and the adjacent faces of the inclined flanges 33 of the shoe. Upon releasing the lever 46, action of the spring 51 rotates bar 43 and moves plates 36 forwardly with respect to the shoes. Such movement causes the rollers 39 to ride along the inclined flange portions 33 to a position such that they effect frictional pressure engagement with the rail 42. Any effort to move the follower rearwardly when the rollers on plate 36 are in the position just described (Fig. 4), merely augments or builds up the pressure engagement of the rollers with the rail. Inasmuch as this means of securing the follower against inadvertent movement longitudinally of the drawer is entirely frictional and not dependent on the location of slots or ribs in the drawer channel, the follower may be located at any exactly desired position in the drawer and will remain in such position, regardless of the pressure of the file contents, until release is effected by movement of the operating lever 46.

Although applicant has shown and described only one modification of his invention, namely, that of a frictional structure for securing a drawer follower in any desired position of adjustment longitudinally of the drawer, it will be understood modifications of the structure shown and described may be made and are contemplated insofar as such modifications are within the spirit and scope of the annexed claims.

Having thus set forth my invention what I

claim as new and for which I desire protection by Letters Patent is:

1. The combination of a drawer having a side channel and an inwardly extending rail; of a follower, a guide shoe on said follower projecting into and being freely movable along said channel, a plate in said shoe, rollers loosely mounted on that portion of said plate located in said shoe and straddling said rail, roller guide means on said shoe, and other means on said follower operable to move said plate and cause said rollers to be moved in a path determined by said guide means, whereby said rollers are brought into clamping engagement with said rail.

2. The combination with a drawer having a side channel and an inwardly extending rail; of a follower, a guide shoe on said follower projecting into and movable along said channel, a pair of bodily movable rollers in said shoe, straddling said rail, an adjustable member mounting said rollers, means constraining said rollers to move into clamping engagement with said rail when bodily moved in one direction by said member, and a lever carried by said follower operable to effect movement of said member in said one direction.

3. The combination with a drawer having a side channel and an inwardly extending rail; of a follower, a guide shoe on said follower straddling said rail and being movable along said channel, a pair of bodily movable rollers in said shoe located one on each side of said rail, guide means in said shoe for directing movement of said

rollers, in one direction, into clamping engagement with said rail, and means carried by said follower operable to effect movement of said rollers into and out of said clamping engagement.

4. The combination of a drawer having a side channel and an inwardly extending rail; of a follower, a guide shoe on said follower projecting into and being movable along said channel, a pair of bodily movable rollers straddling said rail, an adjustable member mounting said rollers within said shoe, means guiding said rollers for movement in a direction to have clamping engagement with said rail when said member is adjusted in one direction, and other means carried by said follower for adjusting said member in the opposite direction to withdraw said rollers from said guide means and relieve the clamping engagement thereof with said rail.
